UNITED STATES PATENT OFFICE.

PHILIP H. OBER, OF MANSFIELD, OHIO, ASSIGNOR TO MANSFIELD TIRE AND RUBBER COMPANY, OF MANSFIELD, OHIO, A CORPORATION OF OHIO.

DESIGN FOR A TIRE.

Application filed April 30, 1924. Serial No. 9,442. Term of patent 14 years.

To all whom it may concern:

Be it known that I, PHILIP H. OBER, a citizen of the United States, residing at Mansfield, in the county of Richland and State of Ohio, have invented a new, original, and ornamental Design for Tires, of which the following is a specification, reference being had to the accompanying drawing, forming part thereof.

The figure is a perspective view of the tire.

I claim:

The ornamental design for a tire, as shown.

PHILIP H. OBER.
